Assistant Examiner — Adrian A Shwaiko

(57) **CLAIM**

The ornamental design for a hedge trimmer, as shown and described.

DESCRIPTION

FIG. 1 is a front view of a hedge trimmer showing our new design;

FIG. 2 is a rear view thereof;

FIG. 3 is a left view thereof;

FIG. 4 is a right view thereof;

FIG. 5 is a top view thereof;

FIG. 6 is a bottom view thereof;

FIG. 7 is a perspective view thereof; and,

FIG. 8 is an another perspective view thereof.

The broken lines depict a boundary around the de-emphasized elements, which illustrate portions of the hedge trimmer which form no part of the claimed design.

1 Claim, 8 Drawing Sheets
